CLAIM

I claim the ornamental design for an irrigation coupling assembly, as shown and described.

DESCRIPTION

FIG. 1 provides a top perspective view of the male and female components of the irrigation coupling assembly showing my new design;

FIG. 2 provides a distal perspective view of the male and female components of the irrigation coupling assembly of the design of FIG. 1;

FIG. 3 provides a proximal bottom perspective view of the male and female components of the irrigation coupling assembly of the design of FIG. 1;

FIG. 4 provides a distal bottom perspective view of the male and female components of the irrigation coupling assembly of the design of FIG. 1;

FIG. 5 provides a top perspective view of the male and female components of the irrigation coupling assembly of the design of FIG. 1;

FIG. 6 provides a proximal perspective view of the male and female components of the irrigation coupling assembly of the design of FIG. 1;

FIG. 7 provides a top plan view of the male and female components of the irrigation coupling assembly of the design of FIG. 1;

FIG. 8 provides a bottom plan view of the male and female components of the irrigation coupling assembly according to the design of FIG. 1;

FIG. 9 provides a first side elevation view of the male and female components of the irrigation coupling assembly of the design of FIG. 1;

(Continued)

FIG. 10 provides a second side elevation view of the male and female components of the irrigation coupling assembly of the design of FIG. 1;

FIG. 11 provides a distal end axial elevation view of the male and female components of the irrigation coupling assembly of the design of FIG. 1;

FIG. 12 provides a proximal end axial elevation view of the male and female components of the irrigation coupling assembly of the design of FIG. 1;

FIG. 13 provides perspective view of the male and female components of the irrigation coupling assembly of the design of FIG. 1 in axial alignment;

FIG. 14 provides perspective view of the male and female components of the irrigation coupling assembly of the design of FIG. 1, where the male component is axially inserted into the female component; and,

FIG. 15 provides perspective view of the male and female components of the irrigation coupling assembly of the design of FIG. 1, where the male component is axially inserted into the female component and rotated into an interlocking position.

The broken lines shown in the figures are for the purpose of illustrating portions of the irrigation coupling assembly that form no part of the claimed design.
